ELECTRIC SWITCH.

1,089,785.

Specification of Letters Patent. Patented Mar. 10, 1914.

Application filed December 1, 1913. Serial No. 804,035.

To all whom it may concern:

Be it known that I, WILBUR G. PEET, a citizen of the United States of America, and residing at Bridgeport, in the county of 5 Fairfield and State of Connecticut, have invented a certain new and useful Improvement in Electric Switches, of which the following is a specification.

My invention relates to electric switches 10 and particularly to switches for electric lamp sockets, the object of my invention being to provide an efficient and inexpensive double break switch mechanism especially adapted for pull sockets and affording both 15 a quick make and a quick break of the switch contacts.

In the accompanying drawing, Figure 1 is a side elevation of a pull socket partially 20 broken away and showing an illustrative embodiment of my invention; Fig. 2 is a horizontal section on the line 2—2, Fig. 1; Fig. 3 is a vertical section on the line 3—3, Fig. 4; Fig. 4 is a horizontal section on the line 4—4, Fig. 3; Figs. 5 and 6 are similar views 25 showing the switch mechanism in different positions; and Fig. 7 is a detached broken perspective of the chain bell and its support.

In the embodiment of my invention here shown, my improved switch is mounted in a 30 lamp socket having the usual cap 10 and shell 11, provided with insulating lining 12. The body of the socket comprises the customary insulating buttons 13 and 14 and these are spaced apart by standards 15 and 35 16, the latter carrying a detachable bell 17 to guide the manually operated pull chain 18. The button 14 carries the usual lamp shell contact 19 and center contact (not shown) the lamp circuit being here broken 40 through the shell contact alone by the switch.

The switch terminals 20 and 21 are 45 respectively connected to the wire terminal 22 and the clamping ring 23 which overlies the base of the screw shell 19. The gap between the switch terminals is spanned in the "on" position of the switch by a U-shaped metal strap 24 mounted on the end of, but insulated by non-conducting material 25, from the oscillating switch yoke 26. The latter is 50 pivoted upon the pins 27 and 28, respectively engaged in the upper and lower buttons 13 and 14. To the stud 29 on the switch yoke 26, one end of the switch spring 30 is secured. The other end of the spring is engaged upon the stud 31 carried by the swing-

ing abutment 32 here shown also in the form of a yoke pivoted upon the pins 27 and 28 and engaged at 33 by the pull chain 18. The extent of oscillation of the abutment yoke 32 may be limited in any suitable manner, 60 for example, by the standard 15 in one direction and by the lug 34 in the opposite direction, the arc subtended between these points being sufficient to permit the abutment end of the switch spring to be shifted 65 by the yoke 32 across the axis of oscillation of the switch yoke 26 when the latter is in either the "on" or "off" position of the switch. The pull chain 18 serves to swing the yoke 32 toward the stop lug 34. The 70 spring 35 coiled on pin 27 engages the yoke 32 and tends constantly to swing it in the direction of standard 15. The tension of this spring may be regulated by displacing the angular head 36 of the pin from its 75 rectangular seat in the button 13 and rotating in either direction, one end of the spring being engaged by said head in well understood manner.

On the lower arm of the abutment yoke 80 32, I mount a pivoted revolving stop piece 37. To assure lightness of operation and freedom of movement, while at the same time preventing this stop piece from spinning under sudden impulse, I support it by 85 means of a headed pin 38 passing up through the lower arm of the yoke 32, and mount on the pin between the head thereof and the yoke arm a lightly compressed coil spring 40. This spring holds the stop 37 in 90 position while at the same time braking its rotation sufficiently to prevent spinning.

The stop 41 against which the stop 37 impinges may be formed in any suitable manner. It is here shown as a raised shoulder 95 on the upper face of the button 14. A deflecting shoulder 42 is also provided to move the stop into inoperative position. As here shown, this shoulder is formed by an 100 upstanding flange on a strap 43 secured beneath the standard 16. The operation of the stop will be readily understood. When the oscillating abutment rests against standard 15, the stop piece 37 lies in the position shown in Fig. 2. As the yoke 32 is swung over on the pull of the chain 18, the point y at the one end of the stop piece 37 impinges against the deflecting shoulder 42 and slides down into the recess 44. The lug 45 on the porcelain not only prevents too great de- 110

lection of the stop piece by the shoulder 42, but also serves to properly position the stop so that upon the return of the yoke 32 under the influence of its spring 35, the other point *x* of the stop piece engages the face *a* of the shoulder 41 and slides out until halted by the face *b* of the shoulder. The yoke 32 is thus halted in the position shown in Fig. 4. Upon the succeeding pull of the switch chain, the point *y* of the stop piece impinges against the face *c* of the lug 45 and is deflected inwardly with the result that the point *x* is swung outwardly to the position shown in Fig. 5. Consequently when the pull chain is freed and the yoke travels toward standard 15 again under the influence of its spring 35, the point *x* lies beyond the face *b* of the shoulder 41 and the stop piece is merely turned freely to the position shown in Fig. 6 as the yoke travels past the shoulder. Upon the succeeding pull of the chain the point *y* of the stop piece is brought into position to engage the face *a* of shoulder 41 and slide into engagement with the stop face *b* of the shoulder in like manner as just described, the cycle of positions being identical for each end of the stop piece.

With the foregoing explanation of the stop mechanism, the operation of the switch is clear. When the switch is "off," the switch yoke 26 and the abutment yoke 32 take the position shown in Fig. 2. On the actuation of the pull chain, the yoke 32 is moved to a position in which the attached end of the switch spring 30 is slightly past the axis of oscillation of yoke 26. Inasmuch as the spring is placed under considerable tension by this movement, the switch yoke 26 is at once swung over with a snap action into engagement with the switch terminals 20 and 21 and thus completes the lamp circuit. As the chain is released, the yoke 32 travels back under the influence of spring 35 to the stop position shown in Fig. 3. But inasmuch as this does not move the abutment end of the spring past the axis of oscillation of the switch piece in its "on" position, the latter remains in engagement with the switch terminal. On the next actuation of the pull chain, the yoke 32 is first moved to the position shown in Fig. 5 (which swings the stop into inoperative position) and then returns under the influence of its spring 35 into engagement with the standard 15 thus shifting the abutment end of the switch spring past the axis of oscillation of the switch piece. The switch piece is consequently snapped back into the "off" position shown in Fig. 2. The position shown in Fig. 6 is that just prior to the full return of the abutment yoke 32 against the standard 15. The friction of the switch terminals 20 and 21 is sufficient to momentarily detain the switch yoke after the abut-

ment has passed the axis of oscillation. As soon as the yoke 32 has touched the standard 15, the switch yoke leaves the switch terminals with a quick break under the pull of the switch spring 30.

This switch mechanism just described constitutes the main feature of the present invention. It is believed however that the mounting of the chain bell on its standard is also specifically novel. The standard 16 has projecting from one side, as above explained, the lug 34. Fitting above and below this lug, I form a pair of claws 46 on one side the chain bell base. On the opposite side, I form a flange 47 with a bead 48 which springs over the edge of the corresponding side of the standard 16. This engagement need not be very strong, since the bell is held in place by the shell of the socket casing, in the assembled condition.

Various modifications of the present device will readily suggest themselves, and I do not limit myself to the precise form shown for the stop piece or the particular construction indicated for halting the switch spring abutment in the "on" position of the switch.

I claim as my invention:—

1. A switch mechanism comprising an oscillating switch piece, a switch spring for actuating the same, a switch spring abutment movable to shift one end of the switch spring across the axis of oscillation of the switch piece in opposite directions, manually operated means for moving said abutment in one direction and means operative only after alternate manual movements of said abutment in one direction, for moving said abutment to shift the abutting end of said switch spring in opposite direction across the axis of oscillation of the switch piece.

2. In a switch mechanism, an oscillating switch piece, a switch spring operatively connected to oscillate the same, a shiftable abutment for one end of the spring, means for shifting said abutment in opposite directions to move the abutting end of the switch spring past the axis of oscillation of the switch piece, and means operatively engaging said abutment to hold the same against operative movement in the one direction after alternate movements in the opposite direction.

3. In a switch mechanism, an oscillating switch piece, a switch spring for actuating the same, a shiftable abutment for one end of said spring adapted to move the abutting end of said switch spring in opposite directions across the axis of oscillation of the switch piece, manually operated means for shifting said abutment in one direction and spring means for returning it in the other direction, in combination with stop means for halting the spring actuated return move-

ment of said abutment before it has shifted the abutting end of the switch spring across the axis of oscillation of the switch piece.

4. In a switch mechanism, an oscillating switch piece, a switch spring for actuating the same, a shiftable abutment for one end of said spring adapted to move the abutting end of said switch spring in opposite directions across the axis of oscillation of the switch piece, manually operated means for shifting said abutment in one direction and spring means for returning it in the other direction, in combination with stop means for intermittently halting the spring actuated return movement of said abutment before it has shifted the abutting end of the switch spring across the axis of oscillation of the switch piece.
5. In a switch mechanism, an oscillating switch piece, a switch spring for actuating the same, a shiftable abutment for one end of said spring adapted to move the abutting end of said switch spring in opposite directions across the axis of oscillation of the switch piece, manually operated means for shifting said abutment in one direction and spring means for returning it in the other direction, in combination with stop means for halting the spring actuated return movement of said abutment before it has shifted the abutting end of the switch spring across the axis of oscillation of the switch piece, and means for rendering said stop inoperative on alternate spring actuated return movements of the switch spring abutment.

6. In a switch mechanism, an oscillating switch piece, a switch spring for actuating the same, a shiftable abutment for one end of said spring adapted to move the abutting end of said switch spring in opposite directions across the axis of oscillation of the switch piece, manually operated means for shifting said abutment in one direction and spring means for returning it in the other direction, in combination with stop means for halting the spring actuated return movement of said abutment before it has shifted the abutting end of the switch spring across the axis of oscillation of the switch piece, and means brought into action by alternate manual operations of the switch spring abutment for rendering said stop means inoperative.

7. In a switch mechanism, an oscillating switch piece, a spring for actuating the same, a shiftable abutment for one end of the said spring adapted to move the abutting end of said switch spring in opposite directions across the axis of oscillation of the switch piece, a spring for moving said abutment in the opposite direction, a stop mounted on said abutment, means engaging said stop when the latter is in predetermined position with relation thereto and serving to halt the abutment during its spring driven travel

before it has shifted the abutting end of the switch spring across the axis of oscillation of the switch piece.

8. In a switch mechanism, an oscillating switch piece, a spring for actuating the same, a shiftable abutment for one end of the said spring adapted to move the abutting end of said switch spring in opposite directions across the axis of oscillation of the switch piece, a spring for moving said abutment in the opposite direction, a movable stop mounted on said abutment, fixed means engaging said stop when the latter is in predetermined position with relation thereto, and serving to halt the abutment during its spring driven travel before it has shifted the abutting end of the switch spring across the axis of oscillation of the switch piece.

9. In a switch mechanism, an oscillating switch piece, a spring for actuating the same, a shiftable abutment for one end of the said spring adapted to move the abutting end of said switch spring in opposite directions across the axis of oscillation of the switch piece, a spring for moving said abutment in the opposite direction, a movable stop mounted on said abutment, fixed means engaging said stop when the latter is in predetermined position with relation thereto, and serving to halt the abutment during its spring driven travel before it has shifted the abutting end of the switch spring across the axis of oscillation of the switch piece, together with means for engaging said stop on alternate manual operation of said abutment and serving to move the same into inoperative position.

10. In a switch mechanism, a switch piece, a switch spring one end of which operatively engages said switch piece, an abutment operatively engaged by the opposite end of said switch piece, said switch and abutment being pivotally mounted on a common axis, means limiting the travel of said switch piece through an arc on one side of said axis, means limiting the travel of said abutment through an arc on the opposite side of said axis, manually operated means for moving said abutment in one direction through its arc to shift the abutting end of the switch spring past said common axis of oscillation, spring means for returning said abutment to shift said abutting end of the switch spring past said common axis of oscillation, and an intermittently acting stop halting said abutment during its spring-driven travel before it has shifted the abutting end of the switch spring across the axis of oscillation.

11. In an electric pull switch, a standard having a lug projecting from one side thereof, a chain bell mounted thereon and having on one side a pair of claws engaging said standard on opposite sides of said lug and having on the other side a beaded flange de-

tachably engaging the corresponding side of the standard, substantially as described.

12. In an electric switch, an oscillating switch piece having the form of a yoke, a strap of conducting material bent over the closed end of the yoke and insulation interposed between said strap and yoke to electrically insulate the same, substantially as described.

13. In an electric switch, a pivoted switch spring abutment, a stop piece pivoted thereon, a fixed shoulder engaging said stop piece in predetermined position and means for moving said stop piece alternately into and out of engaging position, substantially as described.

14. In an electric switch, a pivoted switch spring abutment, a stop piece pivoted thereon, a fixed shoulder engaging said stop in

predetermined position, and means for turning said stop piece on its pivot to bring first one end and then the other end into engaging position, substantially as described.

15. In an electric switch, a pivoted switch spring abutment, a stop piece pivoted thereon, a fixed stop shoulder together with fixed deflecting shoulders engaging said stop piece and serving to move the same alternately, into and out of position to engage said fixed stop shoulder on successive oscillations of said abutment member.

In testimony whereof I have signed my name to this specification, in the presence of two subscribing witnesses.

WILBUR G. PEET.
